SWITCH FOR HAND LAMPS

Walter R. Kopp, New Haven, Conn., assignor, by
mesne assignments, to Western Cartridge
Company, a corporation of Delaware

Application August 25, 1937, Serial No. 160,813

5 Claims. (Cl. 200—60)

This invention relates to switches for use on electrical appliances, such as hand lamps, and has particular reference to a novel switch of the push-button type which is of simple construction and adapted for manufacture at low cost.

One feature of the present invention resides in the provision of a novel switch operable manually by pressing and releasing a push-button and which may be selectively locked in either a closed position or a safety position in which the push-button is ineffective to close the switch. A switch made in accordance with my invention comprises a sliding conductor movable endwise relative to a fixed contact. In one position of the conductor, one end thereof is in lateral alignment with the fixed contact and may be moved laterally by a push-button or the like into engagement with the contact, the conductor moving away from the contact upon release of the push-button. The conductor is movable endwise away from the fixed contact to a position in which it is out of lateral alignment therewith, whereby the conductor will remain disengaged from the contact even when it is moved laterally by the button. The conductor is also movable endwise in the opposite direction into direct engagement with the contact, so that the switch will remain closed independently of the push-button. It will be apparent that in accordance with my invention a switch of simple construction is provided which may be operated intermittently by a push-button and is movable selectively between one position in which the switch is permanently closed and another position in which the push-button when operated cannot close the switch.

Another feature of the present invention resides in the provision of a novel switch of relatively few parts which is positive and reliable in operation.

These and other features of my invention may be better understood by reference to the following description taken in connection with the accompanying drawing, in which

Fig. 1 is an enlarged sectional view of a portion of a hand lamp employing one form of the new switch, the switch being shown in its "off" position wherein the push-button is not adapted to close the switch contacts;

Fig. 2 is a detailed view of the conductor forming part of the switch shown in Fig. 1;

Fig. 3 is a section on the line 3—3 in Fig. 1 showing the push-button of the new switch; and

Fig. 4 is a section on the line 4—4 in Fig. 1

showing the member for sliding the conductor of the switch.

Referring to the drawing, the reference numeral 10 designates a portion of a flash light casing of cylindrical form containing one or more dry cell units 11. As shown particularly in Fig. 1, a disk 12 of insulating material is fitted closely in the cylindrical casing 10 slightly in back of the front end thereof and is seated on an inwardly extending annular bead 13 formed on the casing. The disk 12 is held in position against the bead 13 by bending the front of the casing inwardly over the front of the disk, as shown at 10'. A flanged metal disk 14 is supported in the casing by disk 12 and is in engagement with the back of the latter disk. The disks 12 and 14 are provided with a central opening 15, and secured to the edge of the opening in the metal disk 14 is a lamp socket 16 which extends forwardly through the opening. The socket 16 is formed with a shoulder 16' seated on the front of the insulating disk 12, the portion of the socket forward of the shoulder 16' being threaded to receive a lamp 17.

A strip of spring metal 18 is disposed in back of the metal disk 14 and is spaced therefrom by a strip of insulating material 19 interposed between the metal strip and disk. The metal strip 18 is formed with a detent 18' which projects through a central opening in insulating strip 19 and engages the base contact of bulb 17 when the bulb is threaded tightly in its socket. A contact button 20 of conducting material is mounted on the back of the metal strip 18 and engages the central terminal 11' at the front of the battery. The flanged disk 14, insulating strip 19, metal strip 18 and contact button 20 are held together against the back of insulating disk 12 by a pair of rivets 21 which extend through enlarged openings in the flanged disk 14, whereby no part of the rivets engage the latter disk. It will be apparent that terminal 11' of the battery is electrically connected to the base contact of the bulb 17 through the contact button 20 and metal strip 18, but is insulated from the socket 16 by the insulating strip 19. The other terminal of the battery 11 is electrically connected in the usual manner to the metal casing 10 at the rear thereof (not shown). In order to complete a circuit through the lamp and battery, the casing may be electrically connected to the lamp socket 16 by a switch which will now be described.

A switch slide 22 is seated on the outside of the casing at a convenient place and is held on

the casing by a pair of lugs 23 (Fig. 4) extending from the sides of the slide through parallel longitudinal openings in the casing. The parallel openings through which the lugs 23 extend 5 permit the slide to move back and forth on the casing. A flexible conducting strip 24 is disposed in the casing between the battery 11 and the slide 22. The conducting strip 24 is provided with notches 24' in the sides thereof near the 10 rear end of the conductor, as shown particularly in Fig. 2, and the lugs 23 extend through the parallel openings in the casing and into the notches and are bent inwardly over the inner face of the conductor. Near its front end, the 15 conductor 24 is stamped to provide a central lip which is distorted out of the plane of the conductor in the form of an inwardly extending contact 24'', the contact being disposed slightly in back of the front end of the conductor. A button 25 extends through an opening in the 20 side wall of the casing and is seated on the outer face of the conducting strip 24 intermediate its ends. A pair of lugs 25' (Fig. 3) extend from the sides of the button through spaced parallel 25 openings 26 in the conducting strip and are bent inwardly over the inner face of the conductor to secure the button slidably thereto and thereby prevent the button from falling out of the casing.

30 The flexible conducting strip 24 is adapted to be moved endwise in the casing by the slide 22 and may be locked in any one of three positions by a bowed spring 27 arranged longitudinally in the slide and seated at its ends against the opposite ends of the slide. The spring 27 is formed with a detent 27' which rides on a sinuous portion 28 of the casing when the slide is moved back and forth. With the slide in its retracted position, as shown in Fig. 1, the detent 27' engages the rear end of the sinuous portion 28 and is held thereby against free forward movement. When the slide is forced forwardly against the action of spring 27, the detent 27' rides over the first wave of the sinuous portion 28 and is 35 snapped into a recess 29 which holds the slide in an intermediate position. Further movement of the slide forwardly against the action of the spring causes the detent 27' to ride over another wave of the sinuous portion 28 and snap into another recess 30 which holds the slide in its most advanced position.

In the operation of the hand lamp, the slide 22 is normally in its retracted position, as shown in Fig. 1. In this position of the slide, the front end 55 of the flexible conducting strip 24 is located in back of a rearwardly and inwardly extending circumferential flange 14' on the rear disk 14, the flange 14' forming a fixed contact in the casing. If the conductor 24 in this position is flexed inwardly by pressing the button 25, the front end of the conductor will pass behind flange 14' in spaced relation thereto so that no contact will be made and the lamp 17 will remain de-energized. When the slide 22 is moved forwardly to its intermediate position, the conducting strip 24 is moved therewith to a position in which the portion of the conductor in front of the contact 24'' is in lateral alignment with the flange 14' but spaced therefrom, as shown in the rear dotted line position in Fig. 1. In this position of the slide, the button 25 may be pressed to move the front end of the flexible conductor 24 inwardly into engagement with flange 14', whereby the circuit of lamp 17 and battery 11 is completed 70 through the conductor 24, flange 14', disk 14 and

socket 16. When the button 25 is released, the spring action of the conductor 24 will cause the front end thereof to move outwardly away from flange 14' and thereby break the circuit through the lamp.

The conducting strip 24 may be locked in engagement with flange 14' by moving the slide 22 to its most advanced position. In this position of the slide, the conductor 24 assumes the front dotted line position shown in Fig. 1, wherein the 10 inwardly extending contact 24'' and the front end of the conductor are wedged between the bead 13 and flange 14'. The circuit of the lamp 17 will then remain closed until the slide 22 is moved back to its intermediate or retracted positions. It will be apparent that when the slide 22 is moved back and forth from one position to another, the button 25 will be held stationary by the edges of the opening in the casing through which it extends, the parallel openings 26 in the 15 conducting strip 24 permitting the conductor to slide freely relative to the lugs 25' on the button.

The spring 27 is of simple construction and is held in place in the slide 22 so as to exert sufficient pressure to maintain the detent 27' against accidental displacement in a desired one of the depressions in the sinuous portion 28 of the casing. The slide 22 serves to operate the switch entirely independently of the push-button 25 except when the slide is in its intermediate position wherein the button 25 may be operated to make an intermittent contact of the flexible conducting strip 24 with flange 14'. When the slide 22 is in its retracted or "safety" position, the switch is effectively locked against closure, since the front end of conductor 24 is out of lateral alignment with flange 14' and cannot be engaged therewith by operating the button 25. It will be observed by reference to Fig. 1 that when the slide 22 is moved to its most advanced position, the lip 24'' and the front end of conductor 24 are firmly wedged between the bead 13 and flange 14', and accordingly the circuit through the lamp cannot be accidentally broken when the flash light is jarred.

I claim:

1. A switch comprising a fixed contact, a conductor slidable endwise relative to the contact and movable laterally relative thereto, a manually operable slide for moving the conductor, a sinuous member under the slide, a spring seated at its ends in the slide and normally bowed and having a detent intermediate its ends engageable with the sinuous member, said spring and member being operable to lock the slide selectively in one position in which the conductor is permanently engaged with the contact, in a second position in which the conductor is in lateral alignment with the contact but normally disengaged therefrom and in a third position in which the conductor is out of lateral alignment with the contact, and manually operated means independent of the slide and through which the conductor extends for moving the conductor laterally into engagement with the contact when the member is in said second position.

2. A switch comprising a fixed contact, a flexible conducting strip movable endwise relative to the fixed contact, means for moving the strip endwise between one position in which one end of the conducting strip is permanently engaged with the contact and another position in which the conducting strip is out of lateral alignment with the contact, said strip having a conducting portion disposed inwardly from said end thereof and

laterally aligned with the contact but normally disengaged therefrom when the strip is intermediate said positions, and manually operated means independent of said last means and 5 through which the conducting strip extends for flexing the strip laterally to engage said conducting portion with the contact when the strip is in said intermediate position.

3. In a hand lamp, the combination of a casing, 10 a contact fixed in the casing, a laterally movable member in the casing slidable endwise into engagement with the contact, a slide outside the casing operatively connected to said member for moving the member endwise selectively to one 15 position in which the member is out of lateral alignment with the contact and to another position in which the member is in lateral alignment with the contact but normally disengaged therefrom, and a button extending through an 20 opening in the casing in spaced relation to the slide and having a part bent around said member and through which the member is slidable, the button being operable manually to move the

member laterally into engagement with the contact when the member is in said last position.

4. In a hand lamp comprising a casing and a slide movable to different positions for controlling the lamp circuit, the combination of means 5 for securing the slide against endwise displacement from any of said positions, said means including a fixed, sinuous part, a leaf spring seated at its ends in the slide and normally held by the slide in a bowed form, and a detent on the leaf spring intermediate its ends and movable along 10 said sinuous part by the slide.

5. In a hand lamp, the combination of a casing, 15 an inwardly extending bead on the casing against which the lamp mounting is seated, a contact fixed in the casing and electrically connected to the lamp mounting, and a conducting strip slidable endwise in the casing into and out of engagement with the contact and adapted to be 20 wedged between the contact and said bead.
